(57) **CLAIM**

The ornamental design for a hook tip, as shown and described.

DESCRIPTION

FIG. 1 is a perspective view of the hook tip according to the invention;

FIG. 2 is a right side view of the hook tip;

FIG. 3 is a left side view of the hook tip;

FIG. 4 is a front view of the hook tip;

FIG. 5 is a rear view of the hook tip;

FIG. 6 is a top view of the hook tip; and,

FIG. 7 is a bottom view of the hook tip.

The broken line showing of portion of a hook is for illustrative purposes only and forms no part of the claimed design.
